UNITED STATES PATENT OFFICE.

DAVID CROWTHER, OF MINNEAPOLIS, MINNESOTA.

PROCESS AND APPARATUS FOR DESTROYING ORGANISMS.

1,413,006.

Specification of Letters Patent. Patented Apr. 18, 1922.

Application filed January 20, 1919. Serial No. 271,976.

To all whom it may concern:

Be it known that I, DAVID CROWTHER, a citizen of the United States, residing at Minneapolis, in the county of Hennepin and 5 State of Minnesota, have invented certain new and useful Improvements in Processes and Apparatus for Destroying Organisms, of which the following is a specification.

My invention relates to a process and an 10 apparatus for destroying organisms. The object in particular is the sterilizing of food stuff, the manufacture of vaccine material, and the making of other preparations in which there is life which it is desired to destroy wholly or in part at the lowest possible 15 temperature which is practicable and without materially affecting the chemical composition of the material being treated. The material to be treated may be suspended 20 in water, or may be in the solid state or any other suitable form. The products may be extracted after treatment, if desired, or the organisms may be extracted first from the material and then treated, as for instance 25 in the making of vaccines. For this purpose I employ gases under pressure and preferably those which are most soluble in the liquid contained in the organisms, or in the liquid in which the organisms are suspended. The gases which I employ are also 30 preferably those which have the least chemical action on the materials to be treated. The gas which I prefer to employ for my purpose is carbon dioxide, and in the destruction of spores and spore forming bodies 35 these are suspended in the liquid, and the liquid or mixture is saturated with carbon dioxide under pressure. After the pressure has been maintained for a length of time it 40 is suddenly released, and just prior to, or at the time of release, heat is applied. The heat applied should be only enough to substantially compensate for the cooling action 45 resulting from the sudden expansion of the gas when released.

The full objects and advantages of my invention will appear in connection with the detailed description and the novel features embodied in my inventive idea will be particularly pointed out in the claims.

In the accompanying drawings which illustrate the principle of my invention and the form of apparatus which I may employ,—

Fig. 1 is an elevational sectional view.

Fig. 2 is a similar view of a portion of a slightly modified apparatus.

Referring to the construction shown in the drawings, a receptacle 10, preferably of metal, has a cover 12 adapted to be secured thereto in a suitable manner, as by bolts 14, while a lead gasket 16 may be provided to make a gas tight joint. A screw threaded hole in the cover 12 is adapted to receive the lower screw threaded end of a member 18 60 provided with a vertical bore or chamber 20 closed at the top by a screw plug 22. The hole in the cover 12 is preferably provided with a depending annular flange 24 for receiving a cork or plug 26 through which a 65 glass tube 28 extends from the bore 20 down nearly to the bottom of a glass receptacle 30 placed within the outer receptacle 10. The member 18 is provided with a screw threaded nipple 32 upon which is adapted to be screwed a valve supporting member 34 which contains a valve 36 adapted to control two passageways 38 and 40. The passageway 38 leads to the bore or 70 chamber 20, and the passageway 40 leads 75 through the cover 12 to the space above the receptacle 30. The openings through the valve 36 are so arranged that only one or the other of the passageways 38 and 40 will be open at one time. The outer end of the 80 member 34 is adapted to be connected in any suitable manner, as by a coupling 42 to one end of a tube 44, the other end of which is connected to a gas container 46, such as a 85 carbon dioxide tank. The member 18 is provided with a second screw threaded nipple 48 upon which is adapted to be screwed a valve supporting member 50 which contains a valve 52 adapted to control a passageway 90 54 leading from the chamber 20. The end of the member 50 is adapted to be connected in any suitable manner, as by a coupling 56, to a delivery pipe 58 which leads down into a 95 collecting receptacle 60. The mouth of this receptacle is provided with means for preventing splashing out of the material, and, as shown, this means consists of a wire mesh 62 fitting down into the mouth with cotton 64 supported thereby. The bottom of the receptacle 60 is provided with a faucet 66 100 by means of which the contents may be drawn off. Any suitable means for applying heat to the material being treated, just prior to or at the time of release of pressure, may be provided. Fig. 1 shows a water jacket 68 105 110

around the receptacle 10. This water jacket is provided with inlet and outlet pipes 70 and 72 whereby hot water may be caused to flow through the water jacket to heat the material in the receptacle prior to and at the time of release of pressure, so that there will be no appreciable fall in the temperature due to the sudden expansion of the gas. Fig. 2 shows a water jacket 74 around the 10 horizontal portion of the delivery pipe 58. This water jacket is provided with inlet and outlet pipes 76 and 78 whereby hot water may be caused to flow through the water jacket to maintain the temperature of the 15 material passing through the delivery pipe when the pressure is suddenly released.

The operation and advantages of my invention will be understood from the foregoing description. The material to be treated, such as spores or spore forming bodies in suspension in water, is placed in the glass receptacle 30. The receptacle 10 is then closed and the valve 52 being closed, the valve 36 is turned so as to open communication through 25 the passageway 38 between the tank 46 and the chamber 20. The gas under pressure passes down the tube 28 and out through the liquid in the receptacle 30 so that all of the liquid is subjected to uniform pressure of the 30 gas. The pressure is maintained a sufficient length of time to cause the material being treated to become thoroughly saturated with the gas. The valve 36 is then turned so as to close the passageway 38 and open the passageway 40. This causes the pressure of the 35 gas to be maintained on the top of the liquid in the receptacle 30. Upon turning the valve 52 to open the passageway 54 the pressure on this side of the apparatus is suddenly released and on account of the pressure being 40 maintained through the passageway 40 the liquid will be forced up the tube 28 and through the pipe 58 into the collecting receptacle 60. The sudden release of the pressure 45 bursts the structure of the organisms being treated, with consequent destruction of life. Prior to or at the time of release of pressure, or both, heat is applied to the material in sufficient amount to compensate for the reduction of the temperature which would otherwise occur, due to the sudden expansion of the gas. The organisms are thus not subjected to a temperature which would injuriously affect their properties. At the same 50 time there is no reduction in temperature to lessen the expansive action of the gas on the organisms. It will be understood that on account of the pressure being maintained for nearly the whole length of time through the 55 passageway 38, all of the organisms in the apparatus are subjected to the uniform action of the gas, which would not be the case if the pressure was applied in the first instance through the passageway 40. In the 60 latter case the material would be forced up 65

the tube 28 and the organisms would not be so thoroughly and uniformly subjected to the action of the gas. It will be further understood that by preventing a decrease in the temperature when the gas is allowed to 70 expand suddenly, there is obtained a more rapid disassociation of any carbonic acid (H_2CO_3) that may be formed in the liquid or in the interior of the organisms or material being treated, thus resulting in more certain disruption of the cells and destruction 75 of the life of the organisms.

I claim:

1. The process of destroying organisms which consists in subjecting material to a 80 gas which is inert with relation to the material being treated under pressure for a period of time sufficient to cause the organisms in the material to become saturated, suddenly releasing the pressure whereby the 85 sudden expansion of the gas within the organisms will disrupt the same, and applying sufficient heat to the material to prevent appreciable decrease in the temperature due to the sudden expansion of the gas. 90

2. The process of destroying organisms which consists in subjecting material to a gas which is inert with relation to the material being treated under pressure for a period of time sufficient to cause the organisms in the material to become saturated, 95 suddenly releasing the pressure whereby the sudden expansion of the gas within the organisms will disrupt the same, and applying sufficient heat to the material at approximately the time of release of pressure to prevent appreciable decrease in temperature due to the sudden expansion of the gas. 100

3. The process of destroying organisms which consists in subjecting material to a 105 gas which is inert with relation to the material being treated under pressure for a period of time sufficient to cause the organisms in the material to become saturated, suddenly releasing the pressure on one side 110 of the material while maintaining the pressure on the other side of the material whereby the sudden expansion of the gas within the organisms will disrupt the same, and applying sufficient heat to the material to 115 prevent appreciable decrease in the temperature due to the sudden expansion of the gas.

4. The process of destroying organisms which consists in subjecting material to gas 120 under pressure delivered at one side of the material, cutting off the supply of gas to said side, delivering gas under pressure to the other side of the material, suddenly releasing the pressure on said first mentioned 125 side and applying sufficient heat to the material to prevent appreciable decrease in the temperature due to the sudden expansion of gas.

5. The process of destroying organisms 130

which consists in subjecting material to carbon dioxide under pressure for a period of time sufficient to cause the organisms in the material to become saturated, suddenly releasing the pressure whereby the sudden expansion of the carbon dioxide within the organisms will disrupt the same, and applying sufficient heat to the material to prevent appreciable decrease in the temperature due to the sudden expansion of the carbon dioxide.

6. An apparatus for destroying organisms comprising a receptacle for receiving material to be treated, means for introducing gas under pressure into said receptacle, a delivery pipe in communication with said receptacle, means whereby said delivery pipe may be closed to maintain the pressure of gas in said receptacle and may be opened to release the pressure on said material, and means for applying sufficient heat to the material to prevent appreciable decrease in temperature due to the sudden expansion of the gas.

25 7. An apparatus for destroying organisms comprising a receptacle for receiving material to be treated, means for introducing gas

under pressure into said receptacle, a collecting receptacle having a connection with said receiving receptacle, means whereby 30 said connection may be closed to maintain the pressure of gas in said receptacle and may be opened to release the pressure on said material; and means for applying sufficient heat to the material to prevent appreciable 35 decrease in temperature due to the sudden expansion of the gas.

8. An apparatus for destroying organisms comprising a chamber, a receptacle in said chamber for receiving material to be treated, 40 a source of supply of gas under pressure, connections between said source of supply and said chamber, said connections embodying two passageways, a tube extending down into said receptacle, one of said passageways 45 leading to the top of said tube, the other of said passageways leading to the top of said chamber, means for controlling said passageways whereby either one may be opened while the other is closed, and means for releasing the pressure on said material.

In testimony whereof I hereunto affix my signature.

DAVID CROWTHER.
